UNITED STATES PATENT OFFICE.

ARNOLD AUGUST EGLI, OF BERN, SWITZERLAND, ASSIGNOR, BY MESNE ASSIGNMENTS, TO CHOCOLAT TOBLAR HOLDING CO., AKTIENGESELLSCHAFT, OF SCHAFFHAUSEN, SWITZERLAND.

KEY CONTROLLER.

Application filed July 28, 1923, Serial No. 654,459, and in Germany February 3, 1923.

The invention relates to key controllers and more particularly to controllers of this kind for writing machines or the like. The object of the invention is to enable the pressure to be reduced that has to be applied to a key in operating such machines. This is accomplished by associating with the parts (which otherwise would have to be moved by the force applied to the depressible keys) a cam which is caused by depression of the key to be engaged by a power device, such as a continually revolving cylinder or drum, so as to be operated thereby. A feature of the invention consists in the cam and its detaining means being arranged so that the cam is stopped whenever it has performed the operations assigned to it and is then held stationary even if the key by which it was caused to engage with the power device is kept depressed or in an off normal position. Another feature of the invention consists in means for accelerating the initial rotary movement of the cam and this is accomplished by imparting an impulse to the cam when the key is depressed so that the cam is rapidly brought into engagement with the continually revolving drum or cylinder. The devices for moving the cam detent so as to unlock the cam and for imparting the forward impulse to the cam are preferably united in a single member in the form of a lever or striker moved by the key and kept pressed against the cam by a spring.

The invention is shown by way of example in the drawing in which Fig. 1 is a vertical section showing a key with its associated parts and the power transmitting drum,

Fig. 2 is a plan view of a key according to Fig. 1 and

Fig. 3 shows a combination of two arrangements according to Fig. 1.

In the drawing, 1 is a key in the form of a bell crank lever linked to a striker 2 whose one end is attached to a spring 3, while the other end is opposite to a detent 4. The detent 4 is in the shape of a pawl which engages a tooth of the cam 5 associated with the striker 2, so that the cam 5 is normally prevented from rotating in the direction of the arrow *a*. The striker 2 is provided with a projection 12 which is adapted to drop into a recess 11 in the cam 5. In the normal position of the striker shown in Fig. 1 in full lines the projection 12 lies at a certain dis-

tance from the right hand end of the recess 11. Adjacent to the cams 5 is a motor-driven continually-revolving roll or cylinder 6 which turns in the direction of the arrow as indicated in Fig. 1. 7 is a fork-shaped end of an operable member or bar 8 which is equipped with members that are adapted to prepare or determine the action of subsequently operated devices; for example the operable member may be a part of a register for registering or determining the movements of typebars arranged in a movable magazine from which the typebars may be protruded for the purpose of forming a line of type. When the key 1 is depressed the striker 2 is swung to the right so that first the detent 4 is swung away from the cam 5 and then the striker 2 imparts by means of its projection 12 an impulse to the cam 5 so that it turns in the direction of the arrow *a*. The cam 5 then comes into engagement with the rotating cylinder 6 and is turned round its pivot 5^a and is thus caused to apply pressure to the fork-shaped head 7 of the operable member or bar 8 so as to move the latter in the direction of the arrow *b*. As long as key 1 is held depressed, it retains the striker 2 in raised position as shown in dot and dash lines in Figure 1. In this position, said striker does not interfere with the return movement of detent 4. When the cam 5 has executed a full turn its motion is arrested by the detent 4 which is urged towards the cam by an adjustable spring 9. The striker remains in the position indicated by dash and dot lines, in which position the detent 4 is out of the path of the striker 2 so that the latter cannot affect the detent again until the key has been allowed to return to its normal position. When the key 1 is released by the operator, the spring 3 urges the striker 2 against the cam 5 and restores the key 1 to its normal position.

In Fig. 3 two continually rotating cylinders 6 are shown which impart motion to cams controlled by two groups of keys each comprising three or four rows.

I claim:—

1. In a key-controlled machine, a power-driven roller on a first axis, a plurality of operable members, for each said operable member a cam revoluble round a second axis and adapted to transfer a movement from

- the power-driven roller to an operable member, a detent for keeping a said cam in a normal position, and key-operated means for transitorily disengaging the detent from said cam and permitting it to stop the said cam after a full revolution of the cam in its normal position while the key is depressed.
2. In a key-controlled machine, a power-driven roller, an operable member, a cam adapted to be engaged by the said roller and to transfer a movement from the power-driven roller to the operable member, a detent for keeping a cam in a normal position, means for disengaging the said detent from the said cam, and a key-operated striker for imparting an initial rotary movement to said cam before it is engaged by the power-driven roller.
3. In a key-controlled machine, a power-driven roller, a plurality of operable members, for each said operable member a cam adapted to be engaged by the said roller and to transfer a movement from the power-driven roller to an operable member, a detent for keeping a cam in a normal position, and key-operated means for transitorily disengaging the detent from said cam and permitting it to reengage the said cam in its normal position while the key is depressed and for imparting an initial rotary movement to said cam before it is engaged by the power driven roller.
4. In a key-controlled machine, a power-driven roller on a first axis, a plurality of operable members, for each said operable member a cam revoluble round a second axis and adapted to transfer a movement from the power-driven roller to an operable member, an arresting means in a said cam, a spring-pressed detent with a stopping member adapted for engaging with the arresting means, and key-operated means for transitorily disengaging the said detent from said cam and permitting it to stop the said cam after a full revolution of the cam in its normal position while the key is depressed.
5. In a key controlled machine, a power driven roller, an operable member, a cam for transferring a movement from the power driven roller to the operable member, a detent for keeping the cam in a normal position, a key operated means for transitorily disengaging the detent from said cam and for imparting an initial rotary movement to said cam before it is engaged by the power driven roller, the said key operated means permitting the detent to reengage the said cam in its normal position and adapted to stily disengage the detent from the cam and then impart an initial movement to the cam.
6. In a key-controlled machine, a power driven roller, an operable member, a cam for transferring a movement from the power
- driven roller to the operable member, a detent for keeping a cam in a normal position, and key-operated means for transitorily disengaging the detent from said cam and permitting the detent to reengage the said cam in its normal position while the key is depressed and for imparting an initial rotary movement to said cam before it is engaged by the power driven roller, the said key-operated means consisting in a striker for first operating the detent and for then imparting an initial rotary movement to the cam.
7. In a key-controlled machine, a power-driven roller on a first axis, a plurality of operable members, for each said member a cam revoluble round a second axis and adapted to transfer a movement from the power-driven roller to an operable member, for each cam a spring-operated detent for keeping the cam in its normal position, and a key-operated striker for transitorily disengaging a detent from a cam and permitting the detent to stop the said cam after a full revolution of the cam while the key is depressed.
8. In a key-controlled machine, a power-driven roller on a first axis, a plurality of operable members, for each said member a cam revoluble around a second axis and adapted to transfer a movement from the said roller to an operable member, spring-operated detents for keeping the cams in normal positions, a striker linked to a key, adapted for transitorily disengaging a detent from a cam and permitting the detent to stop the said cam after a full revolution of the cam while the key is depressed, and a spring for urging the striker against the cam.
9. In a key controlled machine, a power driven roller, operable members, for each said member a cam for transferring a movement from the power driven roller to an operable member, spring operated detents for keeping the cams in normal positions, a striker linked to a key, adapted for transitorily disengaging a detent from a cam and permitting the detent to reengage the said cam while the key is depressed, and a spring for urging the striker against the cam and restoring a depressed key to normal.
10. In a key-controlled machine, a plurality of power-driven rollers, operable members, for each roller a cam adapted to be engaged by its roller and to transfer a movement from the said roller to an operable member, a detent for keeping a cam in a normal position, means for disengaging the said detent, and a key-operated striker adapted to engage the said cam on its circumference for imparting an initial rotary movement to said cam before it is engaged by said power-driven roller.
11. In a key-controlled machine, a plurality of power-driven rollers, operable mem-

bers, for each said member a cam for transferring a movement from a said power-driven roller to an operable member, the said cam and roller being revoluble around different axes, a detent for keeping the said cam in a normal position, and key-operated means for transitorily disengaging the said detent from the said cam and permitting the detent to stop the said cam after a full 10 revolution of the cam in its normal position while the key is depressed.

12. In a key-controlled machine, a plurality of power-driven rollers, operable members, for each roller a cam adapted to be engaged by its roller and to transfer a movement from the said roller to an operable member, a detent for keeping a cam in a normal position, means for disengaging the said detent, and a key-operated striker for imparting an initial rotary movement to said cam before it is engaged by a said power-driven roller, the said striker being adapted to act substantially in its longitudinal direction.

13. In a machine according to claim 10 the said striker being substantially longitudinally movable for engaging the said cam.

14. In a key-controlled machine, a power-driven roller on a first axis, a plurality of operable members, for each said operable member a cam revoluble round a second axis and adapted to transfer a movement from the power-driven roller to an operable member, a detent for keeping a said cam in a normal position, and key-operated means for transitorily disengaging the detent from said cam and permitting it to stop the said cam while the key is depressed after the cam has transferred the movement to the said operable member in its normal position, the said detent being normally out of operative connection with the key operated means.

15. In a key-controlled machine, a power-driven roller on a first axis, a plurality of operable members, for each said operable member a cam revoluble round a second axis and adapted to transfer a movement from the power-driven roller to an operable member, an arresting means in a said cam, a spring-pressed detent with a stopping member adapted for engaging with the arresting means, and key-operated means for transitorily disengaging the said detent from said cam and permitting it to stop the said cam while the key is depressed after the cam

has transferred the movement to the said operable member in its normal position, the said detent being normally out of operative connection with the key operated means.

16. In a key-controlled machine, a power-driven roller on a first axis, a plurality of operable members, for each said member a cam revoluble round a second axis and adapted to transfer a movement from the power-driven roller to an operable member, for each cam a spring-operated detent for keeping the cam in its normal position, and a key-operated striker for transitorily disengaging a detent from a cam and permitting the detent to stop the said cam while the key is depressed after the cam has transferred the movement to the said operable member, the said detent being normally out of operative connection with the key operated means.

17. In a key-controlled machine, a power-driven roller on a first axis, a plurality of operable members, for each said member a cam revoluble around a second axis and adapted to transfer a movement from the said roller to an operable member, spring-operated detents for keeping the cams in normal positions, a striker linked to a key, adapted for transitorily disengaging a detent from a cam and permitting the detent to stop the said cam while the key is depressed after the cam has transferred the movement to the said operable member, and a spring for urging the striker against the cam.

18. In a key-controlled machine, a plurality of power-driven rollers, operable members, for each said member a cam for transferring a movement from a said power-driven roller to an operable member, the said cam and roller being revoluble around different axes, a detent for keeping the said cam in a normal position, and key-operated means for transitorily disengaging the said detent from the said cam while the key is depressed and permitting the detent to stop the said cam after the cam has transferred the movement to the said operable member in its normal position while the key is depressed, the said detent being normally out of operative connection with the key operated means.

In testimony whereof I have affixed my signature.

ARNOLD AUGUST EGLI.

CERTIFICATE OF CORRECTION.

Patent No. 1,652,430.

Granted December 13, 1927, to

ARNOLD AUGUST EGLI.

It is hereby certified that the name of the assignee in the above numbered patent should have been written and printed as "Chocolat Tobler Holding Co., Aktiengesellschaft", instead of "Chocolat Toblar Holding Co., Aktiengesellschaft", as shown by the records of assignment in this office; and that the said Letters Patent should be read with this correction therein that the same may conform to the record of the case in the Patent Office.

Signed and sealed this 31st day of January, A. D. 1928.

Seal.

M. J. Moore,
Acting Commissioner of Patents.
